HEAT EXCHANGE APPARATUS

Martin Frisch, New York, and John Blizzard, Gar-
den City, N. Y., assignors to Foster Wheeler
Corporation, New York, N. Y., a corporation of
New York

Application November 2, 1943, Serial No. 508,668

6 Claims. (Cl. 257—262.16)

1

This invention relates to heat exchange apparatus having tubular members, and more particularly pertains to extended surfaces for the tubular members thereof.

The invention provides novel extended surface elements for tubular members of heat exchange apparatus and novel apparatus including tubular members with such extended surface.

The invention will be understood from the following description when considered in connection with the accompanying drawings forming part thereof, and in which:

Fig. 1 is a vertical sectional view of an economizer for a steam generator embodying the invention;

Fig. 2 is a vertical sectional view on line 2—2 of Fig. 1;

Fig. 3 is a cabinet projection of an extended surface element embodying the invention;

Fig. 4 is an elevational view, with parts in section, of a tubular member with extended surface elements of the type shown in Fig. 2, welded thereto;

Fig. 5 is a view illustrating in an exaggerated manner, the action of the hub of an extended surface element of the type shown in Fig. 3, while it is being welded to a tubular member;

Fig. 6 is a cabinet projection of another form of extended surface element embodying the invention, and

Fig. 7 is a longitudinal sectional view of a tubular member with extended surface elements therein which are adapted to be soldered to the tubular member.

Like characters of reference refer to the same or to similar parts throughout the several views.

Although the invention is disclosed as embodied in an economizer for a steam generator, it will be understood that it is not limited to this use, but is capable of application generally to the transfer of heat.

Referring to the drawings, reference character 10 designates a casing for an economizer for a steam generator, having an inner portion 11 forming a passage for products of combustion flowing from the steam generating and super-heating sections of the generator, and outer portions 12 providing housings for the inlet and outlet headers and the return bend portions or connections of the economizer. As shown, the casing 10 is attached to a steam and water drum 13 of the steam generator. Feed water is supplied to the economizer through an inlet connection 14 and is conducted therefrom through an outlet connection 15.

2

The tubular members 16 of the economizer are provided with extended surface elements 17 of the type shown in Figs. 3 and 4. Each element 17 consists of a hub 18 and a flange 19 which is integral with the hub at one end thereof, and extends transversely to the axis of the tubular member on which the element is mounted and is constructed and arranged to provide a plurality, sixteen as shown, of radially extending projections 20, of isosceles trapezoidal configuration in the plane of the projections, the bases of which are spaced a short distance from the hub 18. The hub 18 has a plurality of spaced, longitudinally extending grooves 21 in the inner portion thereof to aid in effectively welding the hubs to tubular members, as will presently appear.

The extended surface elements, in the forms shown for use with steel tubular members, preferably are made of sheet ingot iron having a coefficient of thermal conductivity equal to or greater than that of the tubular members on which they are mounted. The term "ingot" iron, as used herein, refers to an iron of high purity which contains generally less than 0.1% carbon. 25 For steel tubular members of one and one-half inches in outside diameter, extended surface elements made from sheet ingot iron of approximately one-sixteenth inch thickness have been found satisfactory. It will be understood that these figures are given by way of example only and without any limiting effect upon the invention.

The extended surface elements preferably are secured to the tubular members by electric resistance seam welding the hubs 18 of the elements to the tubular members, with the hub of one element in contact with the flange of the next adjacent element as shown in Fig. 4, so that the hubs will provide a covering for each tubular member to shield it from contact with the fluid flowing over the tubular members and the extended surface elements thereon. The major portions of the hubs preferably will be seam welded to the tubular member as indicated at 22 40 in Fig. 4.

The function of the grooves 21 in the interior of the hub 18 will be understood from a consideration of Fig. 5, wherein the seam welding electrode wheels are designated 25 and 26. Due 45 to the pressure of the electrode wheels and to the necessity for clearance between the tubular member 16 and the hub 18 of the extended surface element, at the beginning of and in the early stages of the welding operation, the hub 18 will be forced 50 into an elliptical shape as indicated in Fig. 5,

with air gaps between the tube and the hub in the areas between the welded areas. Moreover, the hub will be heated ordinarily to a higher temperature than the tube, resulting in an expansion of the hub and an increase in its circumference as well as an increase in the air gaps. As the welding proceeds, the circumference of the hub will increase further, due to the plasticity assumed by the metal of the hub. The net result is to cause a shearing stress to be set up 10 between the hub and the tube at the weld which may actually cause the weld to be partially broken as fast as it is made. The grooves 21 provide spaces into which the expanding metal can be forced during welding and they also provide areas of local weakness in the hub so that the metal of the hub can be forced against the tube without deformation of adjacent parts of the hub. Thus the magnitude of the shearing stress is reduced with the result that the hub will tend to 20 keep its original circular shape and the weld will be good. Use of the grooves 21 presents no disadvantage to welding, because a continuous surface is presented to the seam welding electrode wheels, thereby preventing arcing and deterioration of the wheels.

Should it be desired to spot weld the hubs of the extended surface elements to the tubular members, the hubs 18 of the elements may be slotted longitudinally at intervals as indicated at 27 in Fig. 6, for the reasons mentioned in connection with the use of the grooves 21.

In lieu of welding the hubs of the extended surface elements to the tubular members, they may be secured by any other suitable means, if desired. For example, they may be secured by soldering or brazing. Fig. 7 illustrates a form of extended surface element which is particularly well adapted to be silver soldered to tubular members. Referring to Fig. 7, the hub 30 of each element, has an outwardly extending flange 31 at its outer end, which provides sufficient space with the outer surface of the tubular member to receive a ring of silver solder 32. When soldering heat is applied, the solder will melt and will flow into the space between the hub and the tubular member and will secure the element to the tubular member. Any suitable solder may be employed, and the flange 31 need not necessarily be utilized for effective soldering. Preferably, the hub 30 will be continuous and without grooves or slots, for soldering or brazing.

Extended surface elements having a plurality of projections such as the projections 20, are superior from a heat transfer standpoint to a continuous disc of the same diameter and thickness because (a) turbulence of the fluid flowing over the elements is greater with the discontinuous surface, (b) the surface area per unit weight of metal is greater due to the greater edge area, and (c) the least efficient heat transfer surface near the outer periphery of the element is removed, so that the element is made lighter with less than a proportional loss of heat recovering ability.

The number and shape of the projections 20 may be varied as desired, and may be of an even or an odd number. However experiments have shown that the rate of heat absorption per unit of surface of an element of a given thickness increases as the number of projections increases.

The grooves 21 and slots 27 in the hubs of the extended surface elements may be omitted, if desired, and in some circumstances the hub itself need not be used. If the hub is not utilized, the flange with the plurality of projections will be

secured to the tubular member by any suitable means, such as welding, soldering, brazing, or the like.

The forms of the invention disclosed herein are 5 to be considered as preferred forms, and the invention is not to be limited excepting by the scope of the appended claims.

What is claimed is:

1. An extended surface element for a tubular member of a heat exchange device comprising a metallic hub adapted to be mounted on and welded to the tubular member and a plurality of projections in heat exchange relationship with and extending outwardly from the hub, the hub having a plurality of grooves in its inner peripheral portion circumferentially spaced from one another around said periphery and extending substantially parallel to the axis of the hub, the number, size and depth of said grooves being such as to provide areas of local weakness in the hub into which metal of the hub expands during welding and such that the hub can be forced against the tubular member without deformation of adjacent parts of the hub.

2. An extended surface element for a tubular member of a heat exchange device comprising a metallic hub adapted to be mounted on and welded to the tubular member and a plurality of projections integral with and extending outwardly from the hub, the hub having a plurality of spaced grooves in its inner peripheral portion circumferentially spaced from one another around said periphery and extending substantially parallel to the axis of the hub, the number, size and depth of said grooves being such as to provide areas of local weakness in the hub into which metal of the hub expands during welding and such that the hub can be forced against the tubular member without deformation of adjacent parts of the hub.

3. An extended surface element for a tubular member of a heat exchange device comprising a metallic hub adapted to be mounted on the tubular member in heat transfer relationship and a plurality of projections of heat conducting material and of isosceles trapezoidal configuration in a direction normal to the axis of the hub and integral with the hub and extending outwardly therefrom at one end thereof and disposed approximately in a plane extending substantially transversely to the axis of the hub, the hub being adapted to be welded to the tubular member and having a plurality of spaced grooves in its inner peripheral portion circumferentially spaced from one another around said periphery and extending substantially parallel to the axis of the hub, the number, size and depth of said grooves being such as to provide areas of local weakness in the hub into which metal of the hub expands during welding and such that the hub can be forced against the tubular member without deformation of adjacent parts of the hub.

4. Heat exchange apparatus comprising a tubular member and an extended surface element 65 for the tubular member having a hub electric resistance seam welded thereto and a plurality of projections of isosceles trapezoidal configuration in a direction normal to the axis of the hub, the projections extending outwardly from the hub at 70 one end thereof and being disposed approximately in a plane extending substantially transversely to the axis of the hub, the element being composed of ingot iron having a higher thermal conductivity than that of the tubular member, the hub having a plurality of spaced grooves in its

inner peripheral portion circumferentially spaced from one another around said periphery and extending substantially parallel to the axis of the hub prior to the welding of the hub to the tubular member, the number, size and depth of said grooves being such as to provide areas of local weakness in the hub into which metal of the hub expands during welding and such that the hub can be forced against the tubular member without deformation of adjacent parts of the hub.

5. In an economizer for a steam generator comprising a plurality of spaced tubular members in communication with one another to form a fluid flow path, said flow path having a fluid inlet at one end thereof and a fluid outlet at the opposite end thereof, an extended surface element for the tubular members having a hub electric resistance seam welded thereto and a plurality of projections of isosceles trapezoidal configuration in a direction normal to the axis of the hub, the projections extending outwardly from the hub at one end thereof and being disposed approximately in a plane extending substantially transversely to the axis of the hub, the element being composed of ingot iron having a higher thermal conductivity than that of the tubular member, the hub having a plurality of spaced grooves in its inner peripheral portion circumferentially spaced from one another around said periphery and extending substantially parallel to the axis of the hub prior to the welding of the hub to the tubular member, the number, size and depth of said grooves being such as to provide areas of local weakness in the hub into which metal of the hub expands during welding and such that the hub can be forced against the tubular member without deformation of adjacent parts of the hub.

6. An extended surface element for a tubular member of a heat exchange device comprising a metallic hub adapted to be mounted on and welded to the tubular member, heat conducting means extending outwardly from and in a direction normal to the axis of the hub, the hub having grooves in its inner peripheral portion

circumferentially spaced from one another around said periphery and extending substantially parallel to the axis of the hub, said grooves providing spaces into which metal of the hub expands, the number, size and depth of said grooves being such as to provide areas of local weakness in the hub into which metal of the hub expands during welding and such that the hub can be forced against the tubular member without deformation of adjacent parts of the hub.
